UNITED STATES PATENT OFFICE.

WILLIAM L. BRATTON, OF FLATBUSH, NEW YORK.

DESIGN FOR A CURTAIN, &c.

SPECIFICATION forming part of Design No. 20,912, dated July 7, 1891.

Application filed June 8, 1891. Serial No. 395,576. Term of patent 3½ years.

To all whom it may concern:

Be it known that I, WILLIAM L. BRATTON, a citizen of the United States, residing at Flatbush, in the county of Kings and State of New York, have invented and produced a new and original Design for Curtains, Lambrequins, Piano-Covers, and other Upholstery Goods; and I do hereby declare the following to be a full, clear, and exact description of the same, reference being had to the accompanying illustration, forming a part thereof.

The leading features of my design consist of a pattern showing at or near the upper edge a horizontal panel in representation of open lattice-work and under the horizontal panel the representation of vertical panels or stripes of open-work.

The accompanying drawing represents a front view of a curtain, showing my design, in which A represents the textile material of the curtain, B the horizontal panel adjacent

to the top thereof, and under the panel B are represented at C and C² vertical panels or stripes of open-work, the representation of said panels showing that the warp-threads have been removed or dispensed with and that the weft-threads have been tied in bunches. Vertical stripes are also shown at D, in which the warp-threads are represented as removed, but the weft-threads are left unbunched. At the bottom of the curtain a fringe E is represented attached to the textile fabric.

What I claim is—

The design as shown and described. 35
In testimony whereof I affix my signature in presence of two witnesses.

WILLIAM L. BRATTON.
